UNITED STATES PATENT OFFICE.

CLEMENTE STOPPA, OF PHILADELPHIA, PENNSYLVANIA.

CIGARETTE-HOLDER.

SPECIFICATION forming part of Letters Patent No. 340,064, dated April 13, 1886.

Application filed July 9, 1885. Serial No. 171,045. (No model.)

To all whom it may concern:

Be it known that I, CLEMENTE STOPPA, a subject of the King of Italy, and a resident of Philadelphia, Pennsylvania, have invented 5 certain Improvements in Cigarette-Holders, of which the following is a specification.

The object of my invention is to construct a mouth-piece or holder for cigarettes, and this object I attain in the manner which I will 10 now proceed to describe, reference being had to the accompanying drawings, in which—

Figure 1 is a perspective view of my improved cigarette-holder, illustrating the manner in which the same is used. Fig. 2 is a 15 sectional view of the holder on a larger scale than Fig. 1, showing the cigarette clamped; Fig. 3, a view showing the cigarette released, and Fig. 4 a view showing a modification.

The holder shown in Figs. 1, 2, and 3 consists of a tube, A, mouth-piece B, clamping-arms D, and confining-ring F. The tube A is expanded at the front end, a, so as to fit snugly the paper wrapper of a cigarette, this enlarged head of the tube having a conical 25 end, closed with the exception of a number of perforations, b. The inner end of the tube A is also expanded for the reception of a block, d, to a threaded stem, on which is secured the mouth-piece B, and to this expanded inner 30 end of the tube are secured, by means of a ring, f, the inner ends of the clamping-arms D, the outer ends of which are enlarged, so as to form segments, which envelop the inner end of the paper wrapper of the cigarette. 35 When the ring F is moved back on the arms toward the mouth-piece B, the front ends of the arms will, owing to the elasticity of the same, be expanded, as shown in Fig. 3, so that the enlarged head of the tube A can be readily 40 inserted into the end of the cigarette wrapper, the ring being then pushed forward on the arms, so as to compress the same and cause their front ends to clamp the end of the said 45 wrapper and firmly confine the same to the tube A. (See Fig. 2.)

By the use of the improved holder the cigarette can be smoked to the end, whereas when the cigarette is carried directly in the mouth the tobacco and the paper wrapper of the 50 cigarette become saturated with saliva at and

near the inner end, so that a considerable portion of the cigarette is rendered unfit for smoking, and must be thrown away. The length of the tube A, moreover, insures the cooling of the smoke in its passage to the mouth, there being a free play of air around the tube to facilitate 55 this cooling operation.

The use of the tube A with expanded ends is not necessary to the proper carrying out of my invention, as the tube may, if desired, be 60 of uniform diameter throughout. Moreover, the mouth-piece may form part of the tube, and the elasticity of the arms D may be such as to cause them to clamp the wrapper of the cigarette, the expanding of the arms being effected by means of a wedge-ring, as in Fig. 4.

The cylindrical head a of the tube A affords a firm support, to which the inner end of the paper wrapper of the cigarette can be clamped by the elastic arms D, and the conical or flaring head in advance of said cylindrical barrel insures the proper guidance of the wrapper onto the latter without breaking or wrinkling said wrapper.

I claim as my invention—

1. A cigarette-holder consisting of a tube having a mouth-piece and a cylindrical head or barrel, a, in combination with clamps, whereby the paper wrapper of a cigarette may be secured to said cylindrical head or barrel, 75 80 all substantially as specified.

2. A cigarette-holder consisting of a tube having a mouth piece and a cylindrical head or barrel with flaring guide in advance of the same, in combination with clamps, whereby the paper wrapper of a cigarette may be confined to said cylindrical barrel, all substantially as specified.

3. The combination of the retaining arms D with tube A, having a mouth-piece at one end and at the opposite end a conical head with perforations b, as specified.

In testimony whereof I have signed my name to this specification in the presence of two subscribing witnesses.

CLEMENTE STOPPA.
